Primary Examiner—Jeffrey Asch*Attorney, Agent, or Firm*—Oppenheimer Wolff & Donnelly LLP[57] **CLAIM**

The ornamental design for a double column storage tower, as shown and described.

DESCRIPTION

FIG. 1 is a perspective view of a double column storage tower of the present invention;

FIG. 2 is a front elevational view thereof;

FIG. 3 is a right side elevational view thereof; the left side elevational view being a mirror image thereof;

FIG. 4 is a rear elevational view thereof;

FIG. 5 is a top plan view thereof; and,

FIG. 6 is a bottom plan view thereof.

The dotted line showings in the drawings of stored cases are for environmental purposes only and form no part of the claimed design.
